CLAIM

The ornamental design for a lamp, as shown and described.

DESCRIPTION

FIG. 1 is a bottom, front perspective view of a lamp, showing our new design;

FIG. 2 is a rear elevational view thereof;

FIG. 3 is a side elevational view thereof, the opposite side being a mirror image;

FIG. 4 is a top plan view thereof; and,

FIG. 5 is a bottom plan view thereof.

*Fig. 1.**Fig. 2.**Fig. 4.**Fig. 5.*
